UNITED STATES PATENT OFFICE.

JOSEPH FRANCIS O'BYRNE, OF TONOPAH, NEVADA.

METHOD OF PROTECTING AND DECORATING SURFACES.

1,331,822.

Specification of Letters Patent. Patented Feb. 24, 1920.

Application filed February 12, 1917, Serial No. 148,193. Renewed July 19, 1919. Serial No. 312,108.

To all whom it may concern:

Be it known that I, JOSEPH FRANCIS O'BYRNE, a citizen of the United States of America, and residing at Tonopah, in the 5 State of Nevada, have invented certain new and useful Improvements in Methods of Protecting and Decorating Surfaces, of which the following is a specification.

This invention relates to an improved 10 method of protecting and decorating surfaces and to the article produced thereby.

The protection and decoration of surfaces is commonly obtained by the application of paint, varnish, shellac, and the like, directly 15 to the surface to be protected and decorated. The present practice of protecting and decorating surfaces is capable of improvement in several particulars. Foremost among the disadvantages of the present 20 practice is the difficulty of obtaining smooth, highly polished, painted, varnished or like surfaces which will have the desired degree of luster. As is well known, such high finishes are attained only by expert work and the exercise of considerable care. 25 It is also recognized that much time and labor are necessary to produce highly finished coated surfaces and hence another distinct disadvantage, namely, the expense of the present method. Finally, the protective 30 and decorative coating applied to the surface is exposed so that the coating is readily injured by contact with the elements, and by oxidation.

The object of this invention is to provide 35 an improved method for protecting and decorating surfaces and the product therefrom which is characterized in that the surfaces may be treated economically to produce a durable decorative and protective coating 40 and in that the luster of the coating is of improved quality.

Other objects and advantages will appear 45 in the following description and in the appended claims.

The method and product are illustrated in the accompanying drawings, in which—

Figure 1 is a face view of the decorative and protective material;

Fig. 2 is a magnified cross sectional view 50 showing the manner of applying the material to the surface to be decorated; and

Figs. 3, 4, and 5 are magnified cross sectional views, showing various other applications of the method.

Referring to these drawings and particu-

larly to Figs. 1 and 2; reference *a* indicates the surface to be decorated. The material to be decorated and protected may be anything whatever, and surface *a* need not be finished for rough, irregular surfaces may be treated equally as well as the smoothest ones. The paint, varnish, or other coating material employed is not directly applied to the surface *a*, for necessarily this would result in the disadvantages of the ordinary method. That is to say, that even if surface *a* were absolutely smooth, a smooth surface on the paint or the like applied to surface *a* could be only approximated and this only with difficulty and expense. A protective and transparent sheet *b* is applied to surface *a* and upon sheet *b* the coating of paint *c* or the like is applied. Sheet *b* is transparent and any suitable transparent 75 material may be employed. Celluloid may be used and is satisfactory except for its inflammable qualities, and there are other preferably flexible materials, not readily inflammable, and closely resembling celluloid 80 in outward appearance, which are preferred. One example of such material is that now largely used in moving picture films. The invention is, however, in its broader aspect independent of the particular kind of transparent material, and the examples herein given are merely illustrative. The surfaces of sheet *b* are preferably smooth, and the materials closely allied to celluloid generally have exceptionally smooth glasslike 85 surfaces. Upon the smoothness of the surfaces of sheet *b*, the degree of luster obtained by use of the method depends, as will appear.

The paint *c* (indicated in Fig. 1 by line shading for the color blue) is applied to the surface *d* of sheet *b*, and the painted surface is applied to surface *a*, as shown in Fig. 2, so that the paint is seen only through the transparent sheet *b*. The paint *c* need not be applied with particular care to the transparent sheet. In fact, the results obtained by the method are in no wise diminished by dipping the sheet in paint or spraying or pouring the paint upon the sheet. The irregularities in the outer surface of the coating of paint do not matter, and the important feature to note is that, despite the lack of uniformity in the outer surface of the paint coating, the inner surface, which is contiguous to surface *d*, must necessarily be 100 smooth and uniform and to a degree directly corresponding to the smoothness and 105 110

uniformity of sheet *b*. The latter is applied to surface *a* with the paint or like decorating substance against surface *a*, and sheet *b* is attached to surface *a* in any desired manner. For example, the sheet may be secured by screws, tacks, cement, adhesives, or the like or by strips overlapping adjacent sheets or by flanges or any other suitable means, the particular attaching means forming no part of the present invention.

The paint *c*, when seen through the transparent sheet *b*, is absolutely uniform in color and has a high degree of luster which is not obtainable in any other manner known to me as convenient and efficient as this described. The result of high luster necessarily follows from the fact that the visible surface of the paint is made smooth by adhesion to the smooth surface of the transparent sheet. It will be obvious that the painted surface, having improved luster, may be obtained rapidly and at a minimum expense, since care, expert labor, and the usual repeated rubbing down processes are rendered unnecessary. Furthermore, by the method the paint, itself a protecting material, is protected by the transparent sheet *b* and accordingly the surface treated by this method is particularly durable.

30 The invention is capable of general application in the protection and decoration of all surfaces of whatever character. It may be used to advantage in lunchrooms, stores, and other public places. The method may 35 also be advantageously employed in protecting and decorating automobiles. As is well known, the highly finished surfaces of the latter soon lose their luster owing to exposure to the elements and the constant bombardment of minute dirt particles, sand, and the like. The described method, therefore, provides a particularly useful way to obtain the desired lustrous surfaces and to preserve them once they have been obtained.

40 45 If desired, the outer surface of sheet *b* may be in addition painted as indicated at *e* in Fig. 3, and, when the coating *e* becomes worn or loses its luster, it may be readily taken off with a suitable paint remover, revealing the fresh, highly lustrous coating *c* through the transparent sheet. This method may be practised not only to secure a fresh surface but also, if desired, to obtain a fresh surface of different color. Additional colors 50 55 or additional fresh surfaces may be obtained by the method shown in Fig. 4. Here the surface *a* is painted, rubbed down, and polished in the usual way, the coating being indicated by reference *f*. A sheet *g* of protective material, as flannel or the like, is then laid upon the coating *f* and thereafter the transparent sheet *b* having the double coatings *c* and *e*, as described in connection with Fig. 3, is applied. As many fresh surfaces or as many different colored surfaces

as desired may be obtained by adding other sheets *b* having single or double coatings. Thus in Fig. 5 a second protective sheet *g'* may be laid upon the coating *e* and a sheet *b'* having coatings *c'* and *e'* may then be applied to the protective sheet *g'*.

When applied to surfaces which undergo repeated washings—and therefore repeated scratchings—such as the surfaces of automobile bodies, the method exhibits a very 75 distinct advantage—namely, all scratch marks and oxidation dullness may be removed by buffing. To illustrate: Assume that the outer surface of *b*, Fig. 2, to be dulled by repeated washing, oxidation, and 80 scratching. It is obvious that the inner surface, or *d*, has not been touched. Therefore, by means of a buffing wheel on a motor, the outer surface may be buffed to a high polish which will restore the luster 85 and brand new appearance.

Thus an improved method of protecting and decorating surfaces has been provided which is characterized in that durable surfaces of exceptional luster may be economically obtained. The use of the word "paint" throughout the description is intended to include paint, varnish, or any like substance which may be applied for a similar purpose to a sheet of transparent material, as 95 celluloid or like substances or any substances such as glass which may embody the invention for the purpose described, all well known in commerce. The invention has been described in a preferred form with detailed variations for illustrative purposes, but the scope of the invention is defined by the appended claims rather than by the foregoing description.

What I claim is—

1. The method of protecting and decorating surfaces which consists in applying a coat of paint, varnish, or the like to one side of each of a plurality of transparent coverings, in applying one of said coverings to the surface with the painted side in contiguous relation therewith and in successively applying the other coverings painted side down to the first named covering in superposed relation, whereby said surface is protected and decorated by the outermost covering and other freshly painted surfaces may be revealed as the coverings are successively removed.

2. The method of protecting and decorating surfaces, which consists in applying a coat of paint, varnish, or the like to both surfaces of transparent material and in applying said material as a protecting covering to the surface to be decorated, the outer coat being adapted to be removed from said material when the coat becomes worn to reveal a fresh, lustrous inner coat.

3. The method of protecting and decorating surfaces treated with paint or the like,

which consists in applying a covering of protective material to such a surface, in applying a coat of paint, varnish, or the like to one side of transparent material, and in then applying said material as a protective covering to the first named covering with the paint contiguous thereto, whereby the painted surface is protected and decorated and may be revealed when desired by removing said protective coverings.

4. The method of protecting and decorating a surface treated with paint or the like, which consists in applying a covering of protective material to the surface, in applying a coat of paint, varnish, or the like to both sides of transparent material, and in applying said material to the first-named covering, whereby the surface is protected

and decorated with a plurality of coats which may be successively revealed.

5. The method of protecting and decorating surfaces which consists in applying paint, varnish, or the like to both surfaces of each of a plurality of transparent coverings, in applying one of said coverings to the surface to be decorated, in applying a covering of protective material to the last-named covering, and in alternately applying other of said transparent covering and other protective coverings to the first transparent covering in superposed relation, whereby said surface is protected and decorated with a plurality of coats which may be successively revealed.

JOSEPH FRANCIS O'BYRNE.
